UNITED STATES PATENT OFFICE

JOHN ALBERT REID, OF FREDERICTON, NEW BRUNSWICK, CANADA, ASSIGNOR TO THE
HARTT BOOT AND SHOE COMPANY LIMITED, OF FREDERICTON, NEW BRUNSWICK,
CANADA

ARCH SUPPORT FOR BOOTS AND SHOES

Application filed January 12, 1929. Serial No. 332,205.

This invention relates to improvements in arch supports for boots and shoes, and the object of the invention is to provide a support for the longitudinal arch which will 5 provide the requisite support at the medial or inner side of the foot holding the os calcis erect.

A further object is to provide such a support which will effectively support the longitudinal arch without causing rigidity at the 10 point where the shoe normally should bend, thus preventing undue pressure on the sole of the shoe and wear on the sole at the end of the support.

15 A further object is to provide such a support which while effectively supporting the longitudinal arch will add strength to the shoe but at the same time will allow transverse flexibility, so that the normal roll of the foot in walking is not impeded and will allow 20 regular exercise of the plantar muscles.

A further object is to provide such a support which may be so placed in the shoe that the angle of the shank is made to correspond 25 to the tarso-metatarsal articulation of the foot just extending to the tarsal heads of the metatarsal bones, because it is weakness in the tarsus that causes a fallen arch.

30 A further object is to provide such a support wherein the chief strength of the support is at or near the breast of the heel, which primarily takes care of the weight of the body.

A further object is to provide a novel form 35 of support for the longitudinal arch which may be so positioned in the shoe as accurately to meet the requirements of individual feet and shoe sizes so that a single support may serve for a considerable number of shoe sizes and individual foot requirements, thus reducing 40 the production costs by eliminating the necessity of a special support for each shoe size.

A further object is to provide such a support which may be readily incorporated in 45 shoes made on the ordinary lasts, thus further reducing the cost of production by eliminating the necessity of special lasts for the manufacture of shoes equipped with such an arch support.

50 The invention consists in the construction

and arrangement, all as hereinafter more particularly described and illustrated in the accompanying drawing in which

Fig. 1 is a bottom plan view of a shoe equipped with the improved arch support 55 which is indicated in broken lines.

Fig. 2 is a fragmentary longitudinal section through the heel and a portion of the sole of a shoe equipped with the improved arch support.

Fig. 3 is a top plan view of the improved support as would be used for the left foot.

Fig. 4 is a longitudinal section on the line 4—4 of Fig. 3, and

Fig. 5 is a transverse section on the line 5—5 of Figure 3 to a slightly enlarged scale.

In the drawing like characters of reference indicate corresponding parts in the different views.

The improved support comprises a metal shank in the form of a metal plate 10, the front end of which is divided into tongue-like portions 11 by longitudinally disposed slots 12 and these tongues are of decreasing length across the width of the plate, the angle of the front end of the shank being made to correspond with the tarso-metatarsal articulation of the foot, the longest tongue being on the inside of the plate as it would lie in the shoe.

The shank may be made of gradually reduced thickness towards its forward end, the reduction in thickness starting at the base of the tongues 11.

Adjacent to the rear end of the plate is a comparatively large orifice 13, the purpose 85 of which will be later explained and adjacent to the rear end of the plate are tack holes 14 to permit tacking it in place after the proper location has been decided upon, the two tacks 90 being used to keep it from sliding either to one side or the other, that is, the forward end. The plate is so formed that its upper face is concave transversely and convex longitudinally.

In equipping a shoe with the improved arch support, the shank 10 is placed between the insole 15 and the outsole 16 so that the rear end of the shank overlies the heel 17 and the tongues 11 overlie the sole 16 and the 100

shank is secured at its rear end by means of tacks extending through the orifices 14.

The provision of the hole 13 is an important feature in that it permits the centre nail 18 at the front of the breast of the heel to go right through the shank without striking the shank and in this way the shank may extend further back under the heel of the foot than would otherwise be the case and thus provide a much stronger support to the heel. This is an important feature as when the wearer is standing in a shoe, with one of these shanks so positioned in the shoe that the shank extends back well under the heel of the foot, the weight of the foot comes directly on it, that is the wearer's weight alone would almost keep the shank in place.

A further advantage of the provision of the hole 13 is that it enables a single shank to be used for a considerable number of shoe sizes as the shank may be adjusted longitudinally in the shoe as desired for certain sizes and this results in a considerable saving in cost of production, since a comparatively few different shank sizes will take care of practically all men's shoe sizes. The shank is concave transversely on its upper side so that the edges curve upwardly and provide a very efficient support for the longitudinal arch.

The longitudinal arch when it drops does not fall vertically but rather it rolls inwardly allowing the navicular to drop and seemingly protrude and the length of the support is just sufficient to provide the necessary support at the medial or inner side of the foot so as to hold the os calcis erect and the length of the support is just sufficient to accomplish this, but not long enough to cause rigidity at the point where the shoe normally should bend, and in this way undue pressure on the sole of the shoe is prevented and also wear is prevented on the sole at the end of the shank.

It is most desirable in such an arch support to provide the necessary support for the longitudinal arch without causing undue transverse rigidity and due to the construction of the improved arch with its tongues 11 this is effectively accomplished, since a very efficient and effective support is provided and these tongues allow transverse flexibility so that the normal roll of the foot in walking is not impeded, and thus the regular exercise of the plantar muscles is not interfered with.

It will further be noted that the shank is securely anchored between the insole and the outersole and heel.

While the improved support is intended to provide support for the longitudinal arch, it may be conveniently and effectively used in combination with any suitable support for the transverse or metatarsal arch, and when so used it will provide effective relief for

cases in which support is required at both these points.

From the foregoing it will be apparent that the invention provides an improved arch support in the nature of a metal shank whereby the objects set forth are obtained.

Various modifications may be made in this invention without departing from the spirit thereof or the scope of the claims, and therefore the exact forms shown are to be taken as illustrative only and not in a limiting sense, and it is desired that only such limitations shall be placed thereon as are disclosed in the prior art or are set forth in the accompanying claims.

What I claim as my invention is:

1. The combination with a shoe of an arch support comprising an elongated metal plate in the form of a shank disposed longitudinally thereof, the forward end of said plate being divided into longitudinally extending non-diverging tongue-like portions by longitudinal slots, the length of the tongues decreasing from the inner to the outer side of the plate to follow the line of the metatarsal arch, the tongues terminating rearwardly of the metatarsal arch, the rear of said plate overlying the heel of the shoe and anchored thereupon, and the tongue like portions being free from projections for preventing relative movement between them and the sole of the shoe.

2. In a shoe the combination with the heel, the outsole and the insole thereof, of an arch support comprising an elongated metal plate in the form of a shank positioned between the insole and the outsole and having its front end divided into longitudinally extending non-diverging tongue-like portions by longitudinally disposed slots, the tongues terminating rearwardly of the metatarsal arch, the rear end of the plate overlying the heel and anchored thereupon by a nail extending through the heel, outersole and innersole, and the tongue like portions freely overlying the sole, the rear end of the plate being provided with an orifice positioned adjacent the breast of the heel.

3. A device according to claim 2; in which the length of the tongues decreases from the inner to the outer side of the plate to follow the line of the metatarsal arch.

4. In a shoe the combination with the heel, the outsole and the insole thereof, of an arch support comprising an elongated metal plate in the form of a shank positioned between the insole and outsole and having its front end divided into longitudinally extending non-diverging tongue-like portions by longitudinally disposed slots, the tongues terminating rearwardly of the metatarsal arch, the rear end of the plate overlying the heel and anchored thereupon by a nail extending through the heel, outersole and innersole, the tongue like portions freely overlying the sole and

decreasing in length from the inner to the outer side of the plate to follow the line of the metatarsal arch, the plate being concaved transversely, convexed longitudinally and provided with an orifice positioned adjacent

5 the breast of the heel.

5. An arch support for a shoe comprising an elongated metal plate having its front end divided into longitudinally extending tongues, the upper surface of said plate being concave in form to form a partial enveloping support for the os calcis, said plate being of such length as to form such support but not long enough to interfere with normal bending

10 of the shoe when walking.

15 In witness whereof I have hereunto set my hand.

JOHN ALBERT REID.
